ARTHUR J. A. BEYER, OF PHILADELPHIA, PENNSYLVANIA, ASSIGNOR TO JAMES H. BELL, OF PHILADELPHIA, PENNSYLVANIA.

METHOD OF MANUFACTURING KNITTING NEEDLES.

Application filed July 5, 1923. Serial No. 649,532.

My invention relates to the manufacture of knitting needles, more especially of a type used in knitting machines, and is directed primarily towards simplifying such manufacture, improving the construction and formation of the needle, and effecting greater economy in manufacturing costs than has been possible with methods heretofore employed.

Referring to the drawings: Fig. I, is a perspective illustration of the sheet metal blank from which a needle is to be formed.

Fig. II, is a similar view, on an enlarged scale, showing the manner in which one end of the blank is folded preparatory to being rounded into the form of a needle hook.

Fig. III, is a cross-section on a still larger scale, taken as indicated by arrows III—III of Fig. II, and showing the result of the folding.

Fig. IV, is a perspective view, on the same scale as that of Fig. I, showing the bending of the blank to channel or U-beam formation.

Fig. V, is a detail illustration on an enlarged scale showing the first stage of rounding to form the needle hook.

Fig. VI, is a view similar to Fig. V, but showing the hook rounded to its final form.

Fig. VII, is an enlarged cross-section showing the manner in which the folds of the hook are brought into intimate contact to afford a compact cross-section.

Fig. VIII, is a perspective view, also on an enlarged scale, showing an insert filler which I employ to reinforce the needle butt.

Fig. IX, is a detail perspective view, showing the manner in which the filler aforesaid is incorporated in the needle butt.

Fig. X, is a cross-sectional view, taken as indicated by the arrows X—X in Figure IX, further clarifying the manner in which the insert filler is retained in the needle butt.

Fig. XI, is a side elevation of the hook and needle, illustrating the latch in place; and

Fig. XII, is a detail section on a magnified scale, taken as indicated by the arrows XII—XII in Figure XI, and showing the manner in which the pivot for the latch may be formed by inward off-setting of the needle cheeks.

In carrying out my invention, I firstly produce a flat blank 1 from sheet metal, by die stamping or otherwise, of the configuration shown in Fig. I, the thickness of metal being

selected in accordance with the gage of the needle which is to be formed. This blank 1 is in the main symmetrical with reference to its longitudinal median line, it being narrowest at that end marked 2 which is ultimately fashioned into the needle hook. Contiguous to the end portion 2, the blank is configured at opposite sides, to afford outwardly rounded lobes or protuberances 3, 3 that form the needle cheeks which jointly afford bearing support for the pivot of the latch. Beyond the lobes 3, 3, the blank 1 is somewhat reduced in breadth as indicated at 4, said latter portion having parallel sides, and, in turn, being co-extensive with a somewhat broader length 5, the edges whereof are merged into the portion 4 through flaring as at 6. The length 5, just referred to, likewise has parallel edges, and the same is continuous with a comparatively shorter, slightly broadened section 7, juncture between the two being effected through rounded fillets 8—8. The section 7 is flanked at opposite sides by butt projections 9 and 10, whereof the latter is formed with laterally projecting ears or tabs, 11, 11. The opposite sides of the tab 9 are cut away as at 9^a for a purpose hereinafter explained.

According to my improved method of manufacture the end portion 2 is folded longitudinally as shown in Fig. II, the bending being so ordered as to produce a tip having a substantially V-shaped cross-sectional configuration with the vertex rounded, as shown in Figure III, wherefrom the needle hook may be readily shaped without fracture or buckling of the metal.

This folding is followed by a longitudinal folding of the remainder of the blank, as shown in Fig. IV, producing a channel or U-beam formation, the corners being made as sharp as practicable to approximate a rectangular cross-section. As a result of such folding, the lobes 3, 3 are brought into opposing relation, as illustrated. The same is true of the butt projections 9 and 10, and of the side edge profile configuration of the remainder of the blank. If desired, these foldings may be effected in a single operation, but, in order to ensure utmost accuracy and sharper bending in producing the V-shaped cross-sectional configuration of the end portion 2, I prefer to fold it separately.

The needle hook "H" is set up by successive bendings of the folded tip 2 as shown in Figs. V and VI, such procedure preventing fracture and buckling of the metal. After the hook H is fully formed, the sides of the V-section 2 are compressed or clinched into intimate contact so that the bight of the needle hook H is given a smooth inner surface with avoidance of any edge projections likely to injure the thread upon which the needle is to act. The result of this last operation will be manifest from Fig. VII.

After folding of the blank 1, as shown in Fig. IV, the tabs or ears 11, 11 of the butt projection 10 are bent to overlap and envelop the reduced portion of the companion butt projection 9, the parts 9^a accommodating the thickness of the metal as a consequence of which the butt edges are made flush throughout. In order to reinforce the butt "B", I prefer to insert between the projections 9 and 10, a filler 12 also of sheet metal, the same being shown in assemblage in Figs. IX and X, and isolated in Fig. VIII. In bending the tabs 11, I take care that the corners are well rounded as indicated at 13—13, in Fig. IX, so as to ease contact, and facilitate co-operation of the active edges of the finished needle butt with the actuating cams of the machine. If further security of the butt assemblage be required it may be had by spot welding the constituent parts together. Furthermore, if desired, reinforcement may, obviously, be extended using additional fillers at intervals in the channel; or by prolonging the filler through part, or all the length of the channel, of the blank 1 except at the region where the needle latch is to be inserted.

The needle latch, shown at 15 in Figs. XI and XII, may be constructed in any desired manner, and pivoted in any approved way in the interval between the cheeks afforded by the lobes or protuberances 3, 3; but a preferred method of pivoting is to punch the cheek lobes 3, 3 inwardly, as shown at 16, 16 in Fig. XII, to the extent of effecting mutual contact of the trunnions thus produced, such trunnions jointly constituting a pivot for the latch. The last described operation, as will readily be seen, may be effected either as a separate step and the latch 15 subsequently sprung into place, or the two operations of offsetting and latch assembling, effected simultaneously as found most convenient. The trunnions are purposely made so as to afford a maximum bearing area for the latch whereby the latter is amply supported and stayed against lateral play. If desired, the offsetting of the latch pivot trunnions 16, 16 may be done immediately after, or as a part of, the stamping or punching operation whereby the blanks are initially formed.

The production of the latch pivot by punching up the trunnions 16, 16 instead of by piercing the sides of the needle, is desirable

because there is thus provided the necessary resistance of the needle to lateral flexure at the point where the latch 15 is pivoted, which the piercing of the needle tends to break down.

The completed needle, after all the necessary bending operations have been performed, is hardened after approved practice, and is thereby given the desired toughness, accordingly strengthened against flexure, and the metal rendered wear-resistant to the utmost degree. By virtue of the sharp cornered U-shaped cross-sectional configuration, my improved needle is rendered capable of withstanding considerable sidewise flexure without permanent bending or buckling, such as would be likely to result in closure of the longitudinal channel, relative displacement of the latch trunnions or binding of the latch pivot.

Needle production in accordance with my invention is simple, and economical, and the product is comparatively light in weight but characterized by great strength and rigidity and thus capable of resisting the strains to which the needle is subjected in use.

By reason of the thinness of the metal from which my improved needle is constructed, and in consideration of its channeled cross-section, the side walls are rendered sufficiently flexible to yield to irregularities in the groove wherein the needle is guided. As a consequence of these attributes, friction is greatly minimized and binding obviated with avoidance of any longitudinal streaks in the knitted fabric such as ordinarily results by reason of sluggish movements of certain needles in a knitting machine.

Having thus described my invention, I claim:

1. The method of making a knitting-machine needle with integral actuating-butt and hook portions, which consists in folding an elongated sheet metal blank having opposed symmetrically configured edges to channel formation, and clinching the end of said blank remote from the butt to form a substantially solid section hook portion.

2. The method of making a knitting-machine needle with integral actuating-butt and hook portions, which consists in folding an elongated sheet metal blank having opposed symmetrically configured edges to channel formation, clinching the end of said folded blank remote from the butt to substantially solid section, and progressively bending the clinched end to hook formation.

3. The method of making a knitting-machine needle with integral actuating-butt and hook portions, which consists in folding an elongated sheet metal blank having opposed symmetrically configured edges to channel formation, clinching the end of said channeled blank remote from the butt to substantially solid cross-section, progressively bend-

ing the clinched end to hook formation, and fashioning opposed contacting latch pivots in the channeled portion adjacent the aforesaid hook portion.

- 5 4. The method of making a knitting-machine needle by longitudinally folding an elongated sheet metal blank to channel formation, said blank having flanking butt-projections at one end and opposed symmetrically 70 configured edges with outwardly directed lobe portions, clinching the end of said folded blank remote from the butt portion to substantially solid cross-section, progressively bending the clinched end to provide the hook, 75 and forming opposed intimately contacting latch pivots in the lobed portions aforesaid.

- 5 5. The method of making a knitting-machine needle by longitudinally folding an elongated sheet metal blank to channel formation, said blank having flanking butt-projections at one end and opposed symmetrically 80 configured edges with outwardly rounded latch lobes at an intermediate point, clinching the end of said folded blank remote from the butt portion to substantially solid cross-section, progressively bending the clinched end to provide the hook, forming opposed intimately 85 contacting latch pivots in the lobed portion adjacent the aforesaid hook, and overlapping one of the aforesaid butt projections onto the opposed projection.

- 5 6. The method of making a knitting-machine needle by folding an elongated sheet metal blank having opposed symmetrically 90 configured edges and flanking butt-projections at one end into channel formation, one of said butt-projections being formed with lateral extensions, clinching the opposite end of said blank to substantially solid cross-section, progressively bending the clinched end to hook formation, forming opposed intimately 95 contacting latch pivots in the channeled portion adjacent the aforesaid hook formation, overlapping the lateral butt extensions onto the opposed butt-projection, and inserting a reinforcement intermediate said butt projections.

- 5 7. The method of making a knitting-machine needle by folding an elongated sheet metal blank having opposed symmetrically 100 configured edges and flanking butt-projections at one end into channel formation, one of said butt-projections being formed with lateral extensions, clinching the opposite end of said blank to solid cross-section, progressively bending the clinched end to hook formation, forming opposed intimately 105 contacting latch pivots in the channeled portion adjacent the aforesaid hook portion, overlapping said lateral extensions onto the opposed projection, and inserting a reinforcing filler between the flanked projections before overlapping.

- 5 8. The method of making a knitting-machine needle from an elongated sheet metal

blank having spaced up-sets, flanking butt projections and opposed symmetrically configured edges by bending said blank longitudinally to channel formation, clinching the end remote from the butt-projections into 70 solid cross-section with the aforesaid up-sets opposedly contacting to provide latch pivots, progressively bending the clinched end of the blank to hook formation, inserting a filler between the butt projections, and overlapping 75 one said projection onto the other to bind the filler in place.

9. The method of making a knitting-machine needle with integral actuating-butt and hook portions which consists in forming an 80 elongated sheet metal blank having a comparatively narrow portion at the end remote from the butt, and folding the blank longitudinally with the fold of the narrow end portion in intimate contact to form a thread-engaging hook of substantially solid cross-section.

10. The method of making a knitting-machine needle with integral actuating-butt and hook portions, which consists in folding 90 the narrower end of an elongated blank to V-shaped cross-section and the remainder of said blank to U-shaped cross-section, and rounding the end of V-shaped cross-section by successive bendings to substantially solid 95 hook formation.

11. The method of making a knitting-machine needle which consists in forming an elongated sheet metal blank with lateral butt-projections at opposed points, one of 100 said projections having lateral projecting tabs, bending said blank along a longitudinal line with one end thereof brought into intimate contact, and incidentally folding the aforesaid tab projections upon the opposed 105 butt projection.

12. The method of making a knitting machine needle which consists in forming an elongated sheet metal blank with flanking butt projections, one of said projections having lateral tabs, folding the blank longitudinally with folds at one end thereof brought into intimate contact, incidentally bringing the aforesaid butt projections into superposed relation, and bending over the tabs on one 115 of the butt-projections aforesaid to overlap the edges of the companion butt projection.

13. The method of making a knitting-machine needle which consists in forming an elongated sheet metal blank with flanking 120 butt projections at one end, one of said projections having opposed lateral tabs, folding the blank longitudinally to channel formation with the folds at the end remote from the tabs in intimate engagement, incidentally bringing the butt projections into superposed relation, inserting a reinforcing filler in the interval between the superposed butt projections, and bending over the tabs on one of the 125 butt projections aforesaid to secure the filler 130

as well as to overlap the edges of the companion butt projection.

14. As an article of manufacture, a knitting needle having integrally formed butt and hook portions made of longitudinally channeled section with the end adjoining the latch solidified and bent to hook formation.

15. As an article of manufacture, a knitting needle having integrally formed butt and hook portions made wholly of longitudinally channeled section, with the end adjoining the latch portion intimately clinched and bent to hook formation.

16. As an article of manufacture, a knitting-machine needle having integrally formed butt and hook portions made from a sheet metal blank longitudinally folded, with the folded end remote from the butt shaped to thread-engaging hook formation and the remainder of channel cross-section

17. As an article of manufacture, a knitting-machine needle having integrally formed butt and hook portions made from a sheet metal blank longitudinally folded into coincident portions, the folded end remote from the butt being shaped to hook formation, and

a filler inserted in the butt with the intermediate part of channel cross-section.

18. As an article of manufacture, a knitting-machine needle made from a sheet metal blank longitudinally folded into coincident portions, with one folded end in intimate contact and shaped to hook formation, flanking butt projections at the opposed end with the intermediate portion of channel cross-section, and one of said butt projections overlapped onto the other.

19. As an article of manufacture, a knitting-machine needle made from a sheet metal blank longitudinally folded into coincident portions with one folded end in intimate contact and shaped to hook formation, flanking butt projections at the opposite end with the intermediate portion of channel cross-section, one of said butt projections overlapping the other and an interposed filler, and opposed intimately contacting latch pivots adjacent the aforesaid hook portion.

In testimony whereof, I have hereunto signed my name at Philadelphia, Pennsylvania, this 29th day of June, 1923.

ARTHUR J. A. BEYER.
